Primary Examiner — Rosemary K Tarcza*Assistant Examiner* — Seth David Kumpf(74) *Attorney, Agent, or Firm* — Stanek Lemon Crouse & Meeks, PA(57) **CLAIM**

The ornamental design for an uninterruptible power supply, as shown and described.

DESCRIPTION

FIG. 1 is a front perspective view of the uninterruptible power supply showing our design;

FIG. 2 is back view thereof;

FIG. 3 is front view, opposite the back view of FIG. 2;

FIG. 4 is a first side view thereof;

FIG. 5 is a second side view thereof, opposite that shown in FIG. 4;

FIG. 6 is a top view of the uninterruptible power supply; and,

FIG. 7 is a bottom view of the uninterruptible power supply. The broken lines in the drawings illustrate portions of the article that form no part of the claimed design.

It is certified that error appears in the above-identified patent and that said Letters Patent is hereby corrected as shown below:

On the Title Page

Description, FIG. 1:
Please correct “uninterruptible power supply”
To read -- uninterruptible power supply (UPS) --

Description, FIG. 6:
Please correct “uninterruptible power supply”
To read -- UPS --

Description, FIG. 7:
Please correct “uninterruptible power supply”
To read -- UPS --

Signed and Sealed this
Fourth Day of July, 2023
